UNITED STATES PATENT OFFICE.

ARTHUR E. MORTIMER, OF LOS ANGELES, CALIFORNIA.

BASEBALL PUZZLE.

Application filed May 24, 1927. Serial No. 193,778.

This invention has to do with a puzzle, and it is a general object of the invention to provide a unique, attractive and entertaining device of this character.

- 5 It is a general object of the invention to provide a puzzle including a representation of a game field or area and a plurality of balls to be rolled to predetermined positions in the game area.
- 10 Another object of the invention is to provide a game of the character mentioned including various novel features of construction.

The various objects and features of my invention will be best and more fully understood from the following detailed description of a typical form and application of the invention, throughout which description reference is had to the accompanying drawings,

20 in which:

Fig. 1 is a plan or face view of the device provided by this invention;

Fig. 2 is an enlarged, sectional view of the device, being a view taken as indicated by line 25 2—2 on Fig. 1; and

Fig. 3 is an enlarged, sectional view of the device, being a view taken as indicated by line 3—3 on Fig. 1.

The puzzle provided by this invention includes, generally, a plate 10 provided with a plurality of depressions, a plurality of balls 11 operable in the depressions, and a closure 12 applied to the plate to cover the depressions and retain the balls in the depressions.

35 In accordance with my invention, the plate is formed of sheet metal and is made a convenient size and shape. In practice, it is desirable to make the plate rectangular in form, as shown in the drawings, and to proportion it so that it can be conveniently carried in a person's pocket.

The depressions provided in the plate 10, as hereinafter described, are made comparatively deep in the plate so that the balls 11 carried in the depressions are below the top surface of the plate. The cover or closure 12 is formed of transparent material, for instance, celluloid or glass, and is applied to the top of the plate to form a cover or closure for the depressions. A feature of the invention is the arrangement whereby the closure engages or rests on the top of the plate. This makes possible an effective, durable construction, using celluloid, or the like, for the closure. The closure 12 may be held or retained in place on the top of the plate by rolling

or turning the edge portions 14 of the plate so that they engage over the closure, as clearly illustrated in Figs. 2 and 3 of the drawings.

In accordance with my invention, the plate 10 has laid out, or indicated, on it a diagram or representation of a game field and has cup-shaped depressions 15 at points corresponding to the positions of the players of the game. The cup depressions 15 are designed to receive and hold the balls 11. In carrying out my invention, the diagram is indicated or defined on the plate by trough-like depressions 16. The trough depressions 16 are arranged and connected to extend between or inter-connect the cup depressions 15 so that the balls are free to be operated through the troughs to the various cup depressions 15. At points where two or more troughs join or connect at a single cup depression 15, a circular depression 17 is formed around the cup. The purpose of a circular depression 17 at a point such as I have mentioned is to allow a ball to pass from one joining trough to another when a ball is in place in the cup at the connection. In practice, it is desirable to provide a slightly raised rim 18 on the cup depressions 15 located in the circular depressions 17 so that there is a tendency for the balls to pass around the cup rather than drop into them.

Another feature of my invention is the coloring of the several cup depressions 15 different colors and the coloring of the balls 11 so that there is one ball 11 colored to correspond to each cup depression 15. It will be obvious that the depressions and various other parts of the device can be colored or decorated in any suitable manner, and that markings of any desired nature can be applied to the various parts of the device.

In the preferred form of the invention illustrated in the drawings, a baseball field is indicated on the plate 10. The depressions 16 in this case are arranged to indicate a baseball diamond and cup depressions 15 are located at the usual positions of the players on a baseball field. The cup depressions removed from the diamond are connected with the diamond through troughs 16. In the case of a baseball game, as just referred to, a trough 16 may be provided at a point removed from the game field proper to represent the players' bench. This removed trough 16 may be connected with the batter's position at the diamond by another trough 16. With this particular arrangement, the puz-

zle is started with all of the balls 11 arranged in the trough corresponding to the players' bench and, from this position, the operator of the puzzle has to operate the balls through the troughs until all of the balls are in the cup depressions 15 with the colors of the cups and balls corresponding.

From the foregoing description, it will be obvious that my invention provides a unique and interesting puzzle, and it will be apparent that considerable skill and patience are required for a person to manipulate the device to distribute the balls in the manner described. The fact that the cups and balls are variously colored requires each ball to be operated to a predetermined cup, thus making the puzzle far more interesting and entertaining than would be the case if the balls could be arranged in any of the cups.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A puzzle of the character described, including a plate having a plurality of cup depressions corresponding to the positions of players of a game and trough depressions interconnecting the cup depressions, and a plurality of balls for operation through the trough depressions and into the cup depressions, the trough depressions having enlarged portions around the cup depressions where they join at cup depressions.

2. A puzzle of the character described, including a plate having a plurality of cup depressions corresponding to the positions of players of a game and trough depressions interconnecting the cup depressions, and a plurality of balls for operation through the trough depressions and into the cup depressions, the trough depressions having enlarged portions around the cup depressions where they join at cup depressions.

3. A puzzle of the character described, including a plate having a plurality of cup depressions corresponding to the positions of

players of a game and trough depressions interconnecting the cup depressions, and a plurality of balls for operation through the trough depressions and into the cup depressions, the trough depressions having enlarged portions around the cup depressions where they join at cup depressions, the cup depressions occurring at the enlarged portions having slightly raised rims separating them from the enlarged portions.

4. A puzzle of the character described, including a plate having a plurality of cup depressions corresponding to the positions of players of a game and trough depressions interconnecting the cup depressions, a transparent closure secured to the plate close to the top of the plate to cover the depressions, and a plurality of balls for operation through the trough depressions and into the cup depressions, the balls being confined to the depressions by the closure.

5. A puzzle of the character described, including a plate having a plurality of cup depressions formed directly in it corresponding to the positions of players of a game and trough depressions interconnecting the cup depressions, a transparent closure arranged on the plate covering the depressions, edges of the plate being turned over the closure to hold it, and a plurality of balls for operation through the trough depressions and into the cup depressions.

6. A puzzle of the character described, including a plate having depressions in its upper side, balls carried in the depressions, and a transparent closure held in engagement with the top of the plate to confine the balls to the depressions.

7. A puzzle of the character described, including a plate having depressions formed directly in its upper side, balls carried in the depressions, a transparent closure engaging the top of the plate to cover the depressions, and turned parts at the edges of the plate holding the closure.

In witness that I claim the foregoing I have hereunto subscribed my name this 19th day of May, 1927.

ARTHUR E. MORTIMER.
